UNITED STATES PATENT OFFICE.

MERTIE THIERS, OF WICHITA, KANSAS.

AIR-COOLING DEVICE.

1,201,650.

Specification of Letters Patent. Patented Oct. 17, 1916.

Application filed September 1, 1915. Serial No. 48,457.

To all whom it may concern:

Be it known that I, MERTIE THIERS, a citizen of the United States of America, residing at Wichita, in the county of Sedgwick 5 and State of Kansas, have invented certain new and useful Improvements in Air-Cooling Devices, of which the following is a specification.

My invention relates to means for artificially cooling air, and the objects contemplated thereby are the provision of a device in which material having the characteristics of absorption and capillary attraction is employed as a medium for carrying a cooling 15 liquid in such manner that air at a high temperature, upon impinging thereagainst will be cooled and slightly humidified; to provide a device of this character which is extremely simple in construction and arrangement, 20 and which accordingly may be manufactured at a minimum cost; to provide a device which makes it necessary for the circulating air to traverse or take a tortuous course, thereby subjecting the air to the 25 maximum cooling surface; and to provide a device which is thoroughly braced and reinforced at all points so as to effectively resist strong currents or blasts of air.

To the accomplishment of the recited objects and others coördinate therewith, the preferred embodiment of my invention resides in that construction and arrangement of parts hereinafter described, illustrated in the accompanying drawings, and embraced 35 within the scope of the appended claims.

In the drawings:—Figure 1 is a vertical sectional elevation showing my device as adapted to the frame of a window. Fig. 2 is a perspective view partly broken away, of 40 the device removed; and Fig. 3 is a transverse section of the air cooler as shown in Fig. 2.

Referring more particularly to the drawings for a detailed description of my invention the numeral 1 designates a frame comprised of vertical side members 2, an upper reservoir 3 and a lower receiving chamber 4. The reservoir 3 is provided with a supply pipe 5 equipped with a suitable valve 6, and 45 also carries a cover or closure, as 7. Arranged in staggered relation along the bottom of the reservoir 3 are a series of small pin openings 8, and exteriorly of the bottom in alinement with these openings are a plurality of depending bails 9 which serve to support the vertical absorbent tapes or strips 50

10. These tapes are doubled upon themselves or fashioned into endless bands, the vertical parallel portions of which are relatively close together, and at their lower ends 60 they are threaded through the slots 11 in the upper portion of the receiving chamber 4, the slots being made sufficiently large so that their walls will not contact with the said tapes. In order to effectively brace 65 these strips and render them secure against flapping I provide a series of transverse non-corrodible wires or elements 12 which are stitched with respect to the strips, as at 13, and sustained at opposite ends by the vertical side members 2 of the main frame portion. 70

By the way of a single illustration, I have shown my invention fitted to a window frame 14, as exhibited in Fig. 1, although it 75 will be understood that the principle of the device is applicable to various other uses. In this case I may provide an outlet 15 leading from the receiving chamber 4 and designed to supply a similar reservoir as 16 located in the window frame 17, which is just below the uppermost window frame 14, thereby carrying out the idea of continuity 80 of arrangement which obviously would permit of equipping all the windows of large 85 office buildings, hospitals, etc. with facility.

In operation, the valve 6 connected to the main supply pipe 5 is opened thereby permitting a suitable quantity of cool water to enter the reservoir 3. This water trickles 90 through the small pin openings 8 in the bottom of the reservoir and is precipitated upon the upper ends of the several endless bands of tape 10, each series of openings serving 95 to feed the two portions of each strip. The moistening of these bands is manifestly accelerated by reason of the principle of capillary attraction coupled with gravity, and it follows that in a very short time the entire length of the several tapes will be thoroughly saturated with water. Upon the air, which is presumably of a higher temperature 100 than the water, impinging against the surfaces of the moist tapes and being obliged to traverse a well defined zig-zag course, it will readily be seen that the temperature of the air when issuing through the opposite side of my device will be lowered. While it is true that the natural course of the air is interrupted owing to the angular disposition 105 of the tapes, it is likewise true that the air is not subjected to any filtering process, 110

which later would be likely to cause a clogging of the interstices of the tapes. By reason of the relatively close disposition of the parallel portions of the individual tapes, 5 the air entering therebetween will be caused to intimately contact with the moisture and is thereby cooled and slightly humidified. The spaces between the individual endless bands of tape are greater than the spaces 10 between the parallel portions thereof so that too much moisture will not be taken up by the air as it passes therethrough.

It should be understood that in its broader aspect the invention comprehends the employment not only of the various means described, but of equivalent means for performing the recited functions.

While the arrangement shown is thought at the present time to be preferable, it is 20 desired to reserve the right to effect such modifications and variations thereof as may come fairly within the scope of the appended claims.

What is claimed, is:—

25 1. In a device for cooling air, the combination of a reservoir having a series of outlets, a receiving chamber, and two rows of bands of absorbent tape having their upper ends disposed beneath said outlets and 30 adapted to catch the drippings therefrom,

while the lower ends of said bands terminate within said receiving chamber, the bands of one row being arranged in pairs and at substantially right angles to each other, and the bands of the other row being parallel to each other and disposed in close proximity to the angle of each pair of bands in the first mentioned row.

2. In a device for cooling air, the combination of a reservoir having a series of 40 outlets, a depending bail beneath each series of outlets, a receiving chamber, and two rows of bands of absorbent tape having their upper ends connected to said bails and adapted to catch the drippings from said 45 outlets, while the lower ends of said bands terminate within said receiving chamber, the bands of one row being arranged in pairs and at substantially right angles to each other, and the bands of the other row being 50 parallel to each other and disposed in close proximity to the angle of each pair of bands in the first mentioned row.

In testimony whereof I affix my signature in the presence of two witnesses.

MERTIE THIERS.
